(57) **CLAIM**

I claim the ornamental design for a chair, as shown.

DESCRIPTION

FIG. 1 is a perspective view showing the front, top, and side of the chair of the present invention;

FIG. 2 is an elevational view of the front of the chair of the present invention;

FIG. 3 is an elevational view of a first side of the chair of the present invention;

FIG. 4 is an elevational view of the rear of the chair of the present invention;

FIG. 5 is a plan view of the top of the chair of the present invention; and,

FIG. 6 is a plan view of the bottom of the chair of the present invention.

The first side elevational view shown in FIG. 3 is a mirror image of the opposite side of the chair of the present invention.

The dashed line within the figures are for illustrative purposes only and form no part of the claimed invention.
